[57] CLAIM

The ornamental design for a wind chime, as shown and described.

DESCRIPTION

FIG. 1 is a front elevational view of my new design of a wind chime;

FIG. 2 is a rear elevational view with reference to FIG. 2;
FIG. 3 is a top view, also with reference to FIG. 1;
FIG. 4 is a elevational view taken with respect to arrow 4 in
FIG. 3; and,
FIG. 5 is a bottom view.

The view shown in FIG. 4 is provided in lieu of left and right side views of the design since it discloses more fully the ornamental feature of the central portion of the wind chime than a left or right side view would accomplish.
